UNITED STATES PATENT OFFICE.

WILLIAM AMOS, OF PROVIDENCE, RHODE ISLAND.

COMBINED HEATER AND SPARK-CONVEYER FOR RAILROAD-CARS.

SPECIFICATION forming part of Letters Patent No. 435,199, dated August 26, 1890.

Application filed March 15, 1889. Serial No. 303,470. (No model.)

To all whom it may concern:

Be it known that I, WILLIAM AMOS, a citizen of the United States, residing at Providence, in the State of Rhode Island, have invented a new and useful Improvement in Combined Heater and Spark-Conveyer for Railroad-Cars, of which the following is a specification.

The great danger of fire and consequent loss of life in the case of a railroad accident makes it desirable to provide a substitute for the car-heating stoves heretofore employed; and it is also desirable to be able to prevent the sparks from flying into the cars through the open doors or windows.

It is the object of my invention to furnish a practicable device, by means of which the sparks from the furnace of the locomotive can be conveyed to the rear of the train, and the passenger-cars of the train can be properly heated from the exhaust-steam and the escaping products of combustion from the locomotive.

My invention consists in the combination, with the smoke-stack of the locomotive, of a jointed pipe extending to the rear of the train over and through the top portion of the car and provided with joints between the several cars to permit the required angular movement when turning around a curve in the track, and to allow for the necessary vibration of one car with another, and a swinging valve for optionally directing the exhaust-steam and the products of combustion either through the said jointed pipe or through the smoke-stack.

My invention also consists in the improved arrangement for regulating the heat in the car, and in a combination with loose guides, springs, and collars for supporting the pipe-section, which passes through the car, as hereinafter fully set forth.

Figure 1 represents an elevation of a locomotive and train of cars provided with my improvement. Fig. 2 represents a detail view of the ceiling of a railroad-car, showing the under side of the box which surrounds the heating and conveying pipe. Fig. 3 represents a detail side view of the box which surrounds the heating and conveying pipe under the monitor-roof of the car, the said roof being shown in section. Fig. 4 is a detail trans-

verse section of the upper part of a car, showing lateral discharge-pipes extending outward from the main pipe. Fig. 5 is an enlarged elevation of the forward part of the locomotive. Fig. 6 is an enlarged detail section showing the valve for changing the direction of the exhaust either through the heating pipe or through the smoke-stack. Figs. 7 and 8 are enlarged detail views showing the guide for loosely supporting the pipe-section which passes through the car.

In the accompanying drawings, A is the locomotive, B the tender, and C C the passenger-cars of the train.

To the base of the smoke-stack D of the locomotive, and at an acute angle with the same, is attached the heating and conveying pipe E, which passes rearward over the tender, thence over the main roof j of the first car C, and under the monitor-roof f of the same, thus reaching the interior of the car for heating purposes. The exhaust-steam and the products of combustion from the furnace of the locomotive-boiler can be made to pass either directly into the atmosphere through the smoke-stack D, or rearward through the heating and conveying pipe E, by means of the valve F, which is shown in the enlarged section, Fig. 6, the said valve being formed of a flat plate attached to the rock-shaft a, which is located at the angle formed by the junction of the pipe E with the smoke-stack D, and to the outer end of which is secured the arm b. The shaft a is connected to the hand-lever c in the cab of the locomotive by means of the rod d, so that the engineer, by moving the hand-lever c, can direct the exhaust-steam and heated products of combustion, as desired, either wholly through either the heating and conveying pipe E or the smoke-stack D, or partially through both, in which latter case the valve will be set at the intermediate point, as shown in Fig. 6. The engineer can thus control the amount of exhaust-steam and products of combustion to be delivered to the pipe E for car-heating purposes; and in carrying out this part of my invention I prefer to carry the jet-pipe e for the exhaust-steam nearer the base of the smoke-stack D than has been common heretofore, as shown in Fig. 5, the exhaust-pipe being represented

by dotted lines, and the valve F is so arranged that its lower edge can be swung from side to side over the opening in the jet-pipe e at the will of the engineer, thus directing 5 the jet of steam in either direction without materially retarding its velocity. The pipe-section m extends under the monitor-roof f of the car, and is loosely held at its ends by means of the annular guides g g, which fit 10 around the said pipe and are attached to the main roof j. At each side of the fixed guide g and around the pipe-section m is placed a spiral spring h, which is held between a collar i and the said guide, and by means of 15 the said guides and the oppositely-arranged collars and springs proper allowance will be made for the expansion and contraction of the pipe m, and the said pipe will be properly held in position upon the car.

20 The coupling-joint G, between the cars C C, is formed by means of the enlargements n upon the pipes m, which are provided with the flanged rings p for holding the coupling-pipes, the coupling-pipe m'' provided with the enlargement n', and the coupling-pipe m' adapted to enter the enlargement n' of the pipe m'', the said coupling-pipes being supported from the roof j of the car by means of 25 the pipe-holding guides H.

30 The locomotive-tender B is provided with a fixed pipe m⁰, and the coupling G', between the tender B and the forward car C, is formed with a coupling-pipe m''', upon which is placed the movable sleeve n'', which, when moved 35 forward and secured in position by suitable means, will serve to form a bell-shaped enlargement to receive the forward end of the coupling-pipe m'' of the car C, the said coupling-joints G and G' being shown, described, 40 and claimed in my Letters Patent of the United States No. 420,220, to which reference is made for a fuller description of the same.

The pipe m passes through the upper part of the car, immediately under the monitor-roof f, and is inclosed in a box I, the said box 45 being provided at its under side with a series of registers c', which may be opened or closed at pleasure to supply the proper amount of heat to the interior of the car, and other register-openings c'' may be made upon the vertical sides of the box I, as shown in Figs. 3 50 and 4.

At each end of the car C, I arrange the transverse pipes d' d', which are joined to the pipe m, and are each provided with a valve e' for 55 opening and closing the said pipes from the inside of the car, and the said pipes d' d' serve to allow a desired portion of the passing steam and products of combustion to escape laterally from the main conducting-pipe m 60 when not needed for the purpose of heating the car.

I claim as my invention—

1. The combination, with the locomotive smoke-stack and the jointed heating and conveying pipe extending rearward through the car and joined to the smoke-stack at an acute angle, of the jet-pipe for the exhaust-steam, and the valve pivoted at the angle between the smoke-stack and the heating and conveying pipe and adapted to have its lower edge 65 swung from side to side over the discharge-orifice of the jet-pipe, substantially as described.

2. A railway-car provided with a heating 70 and conveying pipe passing through the car and loosely held by the fixed guides attached to the car, and having the springs and the attached collars at opposite sides of the fixed guides, substantially as described.

WILLIAM AMOS.
